Primary Examiner — Melanie Pellegrini(74) *Attorney, Agent, or Firm* — Salter & Michaelson**CLAIM**

The ornamental design for a jewelry product, as shown and described.

DESCRIPTION

FIG. 1 is a perspective view of a jewelry product;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is an exploded perspective view.

The broken lines shown in the drawings showing a chain represent environmental structure which form no part of the claimed design. The remaining broken lines represent portions of the jewelry product which form no part of the claimed design.

1 Claim, 7 Drawing Sheets(56)
